CLAIM

The ornamental design for a swing hammer, as shown and described.

DESCRIPTION

FIG. 1 is a front perspective view of a swing hammer; FIG. 2 is a rear perspective view thereof; FIG. 3 is a front elevation view thereof, the rear elevation view being a mirror image thereof; FIG. 4 is a left side elevation view thereof, the right side elevation view being a mirror image thereof; FIG. 5 is a top elevation view thereof; FIG. 6 is a bottom elevation view thereof; FIG. 7 is another front perspective view thereof; FIG. 8 is another left side elevation view thereof, the right side elevation view being a mirror image thereof; FIG. 9 is another top elevation view thereof; and, FIG. 10 is another bottom elevation view thereof. Environmental structures shown in broken lines in FIGS. 1-10 form no part of the claimed design.

1 Claim, 6 Drawing Sheets
